CHRIST L. NUERMBERGER, OF BUFFALO, NEW YORK, ASSIGNOR TO F. N. BURT COMPANY, LIMITED, OF TORONTO, CANADA, A CORPORATION OF ONTARIO, CANADA.

BOX-MAKING MACHINE.

Application filed March 8, 1923, Serial No. 623,696. Renewed September 29, 1928.

This invention relates to an improvement in box making machines, and with respect to its more specific features to mechanism for assembling tubular box bodies and heads.

5 An object of the present invention is to provide a machine for inserting a plurality of heads in each of a succession of tubular bodies having stops for limiting the inward movement of the heads, wherein the bodies are moved past magazines holding the heads, the heads being fed to the bodies, seated therein, and secured in place.

Another object is to provide in such a machine, means automatically operated for 15 seating the flat heads securely on the stops of the bodies, in substantially the same manner as they would be seated manually, and to press each head firmly down upon the seat.

20 Another object is to so arrange the seating means that it will be controlled by the movement of the feeding means for the heads, the forward movement of the feeding means controlling mechanism to guide 25 the forward edge of the head into engagement with the stop at the side remote from the feeding means, and the rearward movement controlling mechanism to press the rear edge of the head into place on the stop.

30 Another object is to provide mechanism for crimping the extended edge of the body down upon the domed head, to hold the heads in place on the stop, wherein the crimping is done by heat and pressure, to 35 soften and mold the material of the body.

Another object is to provide mechanism for properly positioning the box elements with respect to the crimping mechanism arranged to yield under pressure of a succeeding box element moving into crimping position, thereby to discharge the crimped element.

40 Another object is to provide mechanism for positively disengaging the box element from the crimping mechanism, thereby to insure that the element will be in position to be ejected by the pressure of a succeeding element.

45 Another object is to provide means for operating the several mechanisms in synchronism, so that the several operations of placing the heads and crimping the boxes will be

performed simultaneously on the successive elements.

Another object is the provision of a simple 55 and practical device adapted automatically to feed box bodies and box heads and insert the heads in proper position in the bodies preliminary to their being secured therein.

Other objects will be in part obvious and 60 in part pointed out hereinafter.

The invention accordingly consists in the features of construction, combinations of elements and arrangement of parts which will be exemplified in the construction hereinafter set forth, and the scope of the application of which will be indicated in the following claims. 65

In the accompanying drawings forming a 70 part of this specification wherein similar reference characters refer to similar parts throughout the several views,

Figure 1 is a side view of the improved machine,

Fig. 2 is an enlarged detail in plan of the 75 head feeding mechanism,

Fig. 3 is an end view,

Fig. 4 is a detail in section of the catch for operating the head seating mechanism,

Fig. 5 is a detail of the head seating 80 mechanism showing the first step,

Fig. 6 is a similar view showing the second step,

Fig. 7 is a plan view of the seating mechanism, 85

Fig. 8 is a view similar to Figs. 6 and 7 showing the parts in inoperative position,

Fig. 9 is a vertical section through the domed head magazine,

Fig. 10 is an edge view of one of the front 90 gauge plates with the attached retaining finger,

Fig. 11 is a transverse vertical section at the pusher for transferring the elements to the crimping mechanism, 95

Fig. 12 is a plan view of the same,

Fig. 13 is a detail in front elevation of the crimping mechanism, with the crimping head in section,

Fig. 14 is a view of the crimping head 100 at right angles to Fig. 13,

Fig. 15 is an end view with parts in section of the yielding stop,

Fig. 16 is a view showing the several steps

in the assembling of a box element with the parts in section,

Fig. 17 is an end view with the frame in section and with parts removed, to show the operating shaft,

Fig. 18 illustrates a detail portion of the feed slide operating mechanism.

Fig. 19 is a plan view of the complete machine.

- 10 The present machine is designed to assemble box elements, composed of bodies and heads, wherein the body of the element has a stop near one end for limiting the inward movement of the head. Usually this 15 stop is formed by an inner ring, the body being composed of two rings, fitting one within the other, the inner ring being spaced apart from one end of the body, to provide the stop, which is an annular shoulder. 20 To secure a pleasing appearance in the finished box, the box element forming the cover is provided with a domed head, and to reinforce and brace the box and to securely hold the contents of the box, a flat head is 25 arranged below the domed head, the flat head fitting tightly within the box, while the domed head is relatively loose when first inserted. The heads are secured in place in any desired manner, in the present instance 30 by crimping the end of the body down upon the head. Because of the relatively tight fit between the flat head and the body, the flat head is carefully fitted in place this fitting usually having been done manually. 35 In the present embodiment of the invention a suitable supporting frame 1 is provided, and at the front of the frame an endless conveyor is arranged, for feeding the box elements or bodies to the operating mechanisms. The said conveyor comprises 40 an endless belt 2 supported by rollers 3 and 4, the former being journaled in brackets 5 on the frame, while the latter is journaled in the ends of arms 6 extending laterally 45 from the frame and supported by braces 7. The belt is moved continuously by means of a sprocket chain 8 (Fig. 19) connecting a sprocket wheel 9 on the shaft of the roller 3 with a sprocket wheel 10 on a shaft 11. 50 The shaft 11 journaled in brackets 12 on the frame, is driven from a motor 13 supported by the frame, and connected by a belt 14 with a shaft 15 journaled on one end of the frame. The belt 14 connects wheels 55 16 and 17 on the motor, and on the shaft 15 respectively, and the shaft 15 is connected to the shaft 11 by the chain 8 before mentioned, the shaft 11 having a sprocket wheel engaged by the chain 8.
- 60 A plurality of devices for supplying heads is provided. In the present embodiment, each head supply device includes a magazine arranged alongside of the belt, one of the magazines being adapted to contain flat

heads and the other to contain domed heads, 65 all the heads in each magazine being arranged in superposed relation. The bottoms of the magazines are formed by a table 19 supported above the frame, and the heads are held in superposed relation by means of 70 gauge bars 20, 21 and 22, the bar 22 being between the magazines. Each of the gauge bars 20 is supported by an angle bracket 23, which is secured to a plate 24 supported above the table in spaced relation, so that 75 the lower end of the gauge bar is above the table 19. Each of the gauge bars 21 is also supported by an angle bracket 25 secured to another plate 24. The plates 24 extend longitudinally of the table at the 80 front and rear thereof, and the said plates carry all of the gauge bars. The angle bars 23 and 25 are adjustably connected with the plates 24, by a screw and slot connection indicated at 27, as clearly shown in Figure 2, 85 so that they may be adjusted toward and from the center of the magazine. The gauge bars 22 are supported by a common angle bracket 28, which is mounted in the same manner as the angle bars 23 and 25. Thus 90 each magazine has three gauge bars, arranged at angular intervals of approximately 120 degrees, and the heads are held between the gauge bars.

The table 19 is transversely grooved diametrically of each magazine as indicated at 29 and 30 respectively, and a feed slide is mounted in each groove, the slide in the groove 29 being indicated at 31, while that in the groove 30 is indicated at 32. By 95 means of these slides, heads are simultaneously fed from the magazines toward the conveyor, and the slides are operated by a cam 33 on the shaft 11. The slides are connected by a crosshead 34, and the crosshead 100 is connected to one of the arms of a bell crank 35 by a link 36. The other arm of the bell crank is connected by an adjustable link 37 with one end of a lever 38 having a friction roller intermediate its ends engaging the edge of the cam 33. The other 105 end of the lever is pivoted to an arm 39 depending from the top of the frame. For every complete rotation of the cam, the feed 110 slides will be operated to feed a flat and a domed head to box bodies on the conveyor.

Retaining fingers are provided in each magazine, for preventing the passage of more than a single head, the said fingers being mounted on the gauge bars 20. As 115 shown in Figures 9 and 10, each of the retaining fingers 40 is slidably connected with the gauge bar, by screw and slot connections 120 41. Normally the retaining fingers occupy the position of Figure 10, with their lower ends contacting with the table 19. The inner corners of the fingers are beveled how- 125

ever, so that when a head is moved toward the conveyor by the slide, the retaining finger will be lifted by the head, to permit the passage thereof from the magazine. The 5 forward under corner of the slide 31 is beveled, as shown in Figure 3, and the upper face of the slide is flush with the upper face of the table 19. A pushing finger 42 is secured to the inner end of the slide, 10 for engaging the bottom head, and when the slide is reciprocated, a head is pushed out past the retaining finger, and into position above a box body A supported by the conveyor.

15 In the illustrated embodiment, the inserting of the head in the box is controlled by the movement of the slide. The inserting mechanism includes a rock shaft 43 journaled in arms 44 extending above the conveyor from the table 19, and the shaft has a finger 45 intermediate the arms, and in position to engage the forward edge of a flat head fed by the slide, and guide the said forward edge into the box body. The shaft 20 has an arm 46 at one end, in position to be engaged by the end of an operating bar 47, connected to the rear of the slide 31 by a bracket 48. When the slides move toward the conveyor, the end of the bar 47 engages 25 the arm 46, rocks the shaft 43 and causes the finger 45 to engage the forward side of the head, and to press the forward edge of the head into the body, and down upon the shoulder.

30 The mechanism for pushing the rear of the head into the box (see Fig. 5) includes a plate or finger 49 shaped to fit within the body, and substantially semi-circular in form. This plate is carried by arms 50 extending upwardly and rearwardly from a shaft 51, journaled in bearing arms 52 extending from the table 19, above the conveyor. The plate is connected to the arms by links 59, which are pivoted to the plate 35 and to the arms. A spring 53 (see Fig. 7) encircles the shaft 51 between one of the arms and a stop 54 thereon, and the spring normally acts upon the shaft to lift the plate 45. The bar 47 has guided movement in 40 supports 55 extending upwardly from the table, and at its forward end it has a chamber in which is pivotally mounted a catch 56. The catch is normally forced downward, by a spring 57, and the forward end 45 is cam shaped to ride over a lug 58 on the end of an arm oscillatable with the shaft 51, and to engage in front of the lug, as shown in Figure 6, so that when the slide 31 moves rearwardly, the shaft will be rocked, and the 50 plate 49 will be depressed into engagement with the rear side of the flat head, and will force the head down into the body.

55 Means is provided for guiding the plate 49 in its vertical movement, the said means including an angle guide bar 60 rigid with

the plate 49 which upstands from said plate and passes between the forward end of an extension of a presser foot 61 to be presently described, and the shaft 51. The presser foot has an upwardly extending rod 62 at 70 the end adjacent to the magazine, which is 75 slidable in a housing 63, secured to the adjacent plate 24 between the arms 52. The rod has a head 65 within the housing, and pins 64 extend radially from the head through vertical slots in the housing, to prevent rotation of the rod. A spring 66 is arranged between the head and the housing, and acts normally to press the foot downwardly and to lightly clamp the oncoming 80 head against the table. The inner end of the foot is beveled or rounded as shown, so that the oncoming head may lift the foot. The presser foot does not engage the table except when the presser plate 49 moves 85 downward, the foot being normally elevated by the presser plate, as shown in Figure 5.

90 The operation of the parts just described is as follows—

When the slide 31 moves forward, the 90 plate 42 engages the lowermost head in the pile, and pushes it past the retaining finger, beneath the foot 61, and above the box body A, the foot holding the head in a substantially horizontal plane. As the forward 95 edge of the head approaches the front side of the box body, the bar 47 engages the arm 46, and rocks the shaft 43. The finger 45, which is beveled on its under face engages the top of the head, and guides the head 100 downward into position against the stop in the box body. The forward movement of the slide continues, until the head is in the position shown in Fig. 5. Meanwhile, the catch 56 has ridden over the lug 58 and is in 105 front of the same. When now the slide moves rearwardly, the finger 45 is lifted by the spring 67, which is connected to arm 46, and the catch 56 engages the lug and rocks the shaft 51. The plate 49 is moved downwardly, and as it reaches the position of 110 Figure 6, the angle plate 60 is engaged between the forward end of the bar 61 and the shaft 51, and is held vertically. This plate is at right angles to the plate 49 and as a 115 consequence of the vertical movement of the plate 60 the plate 49 is held horizontal, pushing the head down upon the stop of the box body, in the exact position desired. When the feed slide moves rearwardly, the catch 56 120 rides over the lug 58, by snapping past said lug, and the spring 53 returns the shaft 51 to normal position, lifting the plate 49 to the position of Figure 5. As the plate lifts the under surface thereof engages the under 125 face of the extension of foot 61, lifting the foot, also, the spring 53 being stronger than the spring 66. Referring to Figures 5 and 6, it will be seen that the under face of the foot 61 is notched to receive the plate 49, so 130

that the under face of the plate at the inner edge thereof is above the lower face of the foot 61, and does not interfere with the movement of the next head into position 5 above the succeeding box body.

After a flat head has been inserted in the box body, and at the completion of the operation, a box is removed from the conveyor to the crimping mechanism, and the succession of box bodies on the conveyor is advanced a step. The box in which the flat head has just been placed is now supplied with a domed head, this operation being simultaneous with the placing of a flat head 10 in the succeeding body. Referring to Figure 9, it will be noticed that the domed heads rest at their rear edges on a plate 68, which extends inwardly in inclined position from the rear gauge bar 21. The plate extends 15 transversely of the groove 30. At each end of the plate pins 69 extend upwardly from the table 19, the said pins engaging the edge of the lowermost blank in the magazine to position it exactly. The heads are arranged 20 with their convex surfaces upward, in nested relation, and to move the blanks in succession, the slide has a sharp-toothed pawl 70 at its forward end. The slide 32 is of greater length than the slide 31 being of such 25 length that when the slides are in retracted position, and the forward end of the slide 31 is at the rear of the flat head magazine, the toothed end of the plate 70 will be near the forward side of the domed head magazine. 30 When the slides move forwardly, the toothed end of the plate 70 engages the concave face of the lowermost head, near the forward edge thereof, and pushes the head out beneath the retaining finger 40 and into position above 35 a box body. Retraction of the head with the slide is prevented by a retaining member in the form of a yoke, the arms 71 of which extend through openings in the adjacent plate 24. The body 72 of the yoke normally 40 rests on the plate 24, and it has a guide pin 73 passing through the overlying portion of an angle bracket 74 secured to the plate 24. The lower rear corners of the arms 71 are beveled, as shown in Figure 9, so that when 45 a domed head moves forward the retaining member is lifted, and does not interfere with the forward movement of the head. The retaining member however, prevents rearward movement of the head and insures that it will fall into that box body which is at 50 the magazine for domed heads.

It will be noted that the arrangement hereinbefore described results in the simultaneous insertion into two of the box bodies 55 of heads from each magazine, the head from the dome supply magazine being inserted after the head from the other magazine, but the heads being laid in the box bodies practically at the same time. It will also be 60 observed that inserting mechanism for the

flat heads disposes the heads, or the front and rear sides thereof, in tilted relation to the plane of the edge of the opening into which they are to be inserted, one side of head first entering the opening, to be followed by the remainder of the head, the fingers 45 and 49 acting as it were in a sequential order so that one finger inserts part of the head before insertion of the complete head is effected by the inserting movement 65 of the other finger. Thus, although the heads are of different shapes and come from different sources, their insertion in two box bodies is effected at the same time as in one, the facility for disposing the closely fitted 70 flat head being substantially equal to that of inserting the more loosely fitting dome head, on account of the special manner in which the flat head is pressed into its body. It will also be noted that the feed slide 32 immediately in rear of the toothed pawl 70 is sufficiently wide to support the dome head above the box body into which it is to be inserted, this dome head being stripped from the slide 75 upon retraction of the latter. 80

Upon the completion of the operation of placing a domed head in the box body, which is simultaneous with the completion of a crimping operation, another box body is moved from the conveyor to the crimping mechanism, and the box bodies on the conveyor are again advanced, to bring succeeding box bodies in position to receive flat and domed heads. As the boxes provided with heads move onward, they eventually engage 85 a stop 75 (Figs. 2, 11 and 12) extending transversely above the conveyor, at the crimping mechanism. A pusher 76 is arranged to move transversely of the conveyor, near the stop 75, and on the opposite side of the conveyor from the magazines. This pusher, which is in the form of a slide, is movable in a guide 77 supported by the frame 1, and it is operated by a cam 78 on the shaft 11 before mentioned. A slotted follower 79 embraces the shaft, and has a friction roller 80 engaging the edge of the cam. The friction roller is held in engagement with the cam by means of a spring 81 arranged between it and an extension 82 from the frame, and the follower is connected with one of the arms of a bell crank 83 whose other arm is connected to the pusher by a link 84, the said link having a turn buckle interposed in its length as shown in Figure 11. A second spring 85 is arranged between 90 the lower arm of the bell crank and the bracket 86 which supports the guide 77, and acts normally to move the slide outwardly, and the spring 81 assists this action. 95

The opposite sides of the upper run of the belt 2 move upon rails 87 and 88 which are supported from the frame 1, the rails 100 extending from the roller 3 to the roller 4. Guides 89 are secured to these rails, the 105

said guides being spaced slightly from the edges of the belts, and the belt runs between the guides which are in the form of angle plates, having one portion secured to the adjacent rail, and another portion extending vertically therefrom. The stop 75 is the continuation of a rail 90, which is one of a pair forming a guide for the box body from the conveyor to the crimping mechanism, the other rail being indicated at 91 in Figures 2 and 12. The rails 90 and 91 are secured to a plate 104, which extends from near the belt 2 to the crimping mechanism.

15 The crimping mechanism includes a bracket 92 having an overhanging arm, through which is threaded a rod 93 (see Fig. 13), carrying at its lower end a block of metal 94, and having at its upper end a wheel 95, by means of which the rod may be turned to establish the position of the block. The block which is rectangular in cross-section moves against the vertical face of the bracket, and the block is adapted to be heated, having openings as shown into which heating mechanism, as for instance gas jets or heating coils may be inserted. A head 96 is detachably connected with the lower face of the block, by means of screws 97 passing through the block and engaging the head, and the head is provided in its under face with an annular groove 98, which is shaped to gradually turn in the edge of the box body as it is moved upward 25 into engagement with the head, by mechanism to be described. The head is recessed centrally as shown at 99 and a crown 100 is arranged within the recess, the lower face of the crown being concave to fit the domed head.

30

The box bodies with inserted heads are moved over the plate 104, between the rails 90 and 91 onto a table 101 arranged directly beneath the crimping head, and having fixed stops 102 at its opposite sides, between which the box is moved, into engagement with a movable stop 103 at the end of the table. The stop 103 is hinged to the table as indicated at 105, and is normally held 35 against the end of the table and extending above the upper face thereof by a coil spring 106. The stops 102 and 103 are positioned to support the box directly beneath the crimping head, and in position for the edge thereof to be engaged by the turning groove, and the spring 106 is of sufficient strength to check the movement of the box at the proper point, but to yield under the pressure of a succeeding box, to permit the crimped box to be discharged from the table 40 101 away from the machine.

45 The table 101 is moved vertically toward and from the crimping head by means of a cam 107 secured to the shaft 11. The table is at the upper end of a slide 108

having guided movement in a vertical bearing 109 supported by the table 1, and provided with a friction roller 110 engaging the edge of the cam. When the table is moved upward, the upper edge of the box 70 body thereon will engage the turning groove 98, and the said edge will be crimped and molded inwardly upon the domed head, securing both heads in place.

Mechanism is provided for insuring the 75 discharge of the crimped body from the crimping head. The crown 100 is adapted to be moved downward after the crimping, by means of a cam 111 on the shaft 11. This cam engages a friction roller on a lever 80 112 pivoted to a bracket 113 depending from the table 1, and connected by a link 114 with one end of a lever 115, pivoted at 116 to the bracket 92. The lever 115 has an opening through which the rod 93 passes, 85 and at each side of the rod the lever engages headed pins 117, which are mounted to slide through the block 94, and are connected with the crown 100. Springs 118 are arranged between the heads of the pins 90 and the block, and act normally to hold the crown close within the recess 99. The friction roller of the lever 112 is held in close engagement with the cam by means of a coil spring 119 arranged between the table 95 1 and the lever.

When a body with inserted heads has been moved into engagement with the stop 103, the cam 107 operates to lift the table 101. The end of the box body engages the head 96, and the material of the end is softened, and molded down upon the domed head. At the moment the table begins to descend, the cam 111 operates to depress the crown 100, and the crimped body is discharged from the head. When a succeeding body is moved toward crimping position, the head just crimped is discharged, the stop 103 yielding to permit the discharge. The crimped body passes from the 105 machine over an inclined discharge table 120. All of the operating parts are adjustable to insure coordination, the links 37, 84 and 114 having turn buckles interposed in their length, to permit them to be lengthened or shortened.

Referring to Fig. 9, it will be noticed that the domed heads in the magazine are supported by the slide 32, and by the plate 68, when the slide is in its forward position. 120 When the slide moves rearwardly, the front edge of the lowermost head drops, and the concave face thereof, near its forward edge, is in position to be pierced by the teeth of the plate 70, which are relatively sharp, so 125 that they will engage positively the head. As the slide makes its forward movement, the lowermost head is caught by the teeth and pushed out beneath the elements 40, which lift to permit the passage of the head 130.

and the slide, and the lowermost head is carried out of the magazine, the stack of heads being supported by the slide and the plate 68.

The operation of the machine will be understood from the description of the operation of the several mechanisms. The box bodies are fed to the belt 2, as for instance manually. As each body comes into position at the flat head magazine, a flat head is inserted therein. Afterwards a domed head is placed on the flat head, and the end of the box is crimped down upon the domed head.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention, which, as a matter of language, might be said to fall therebetween.

Having described my invention, what I claim as new and desire to secure by Letters Patent is:—

1. In a machine of the class described, in combination, means for inserting heads in tubular box bodies, comprising a support for the body, means for feeding a head to the body, means for positioning the advance end of the head in the body, and means for pushing the rear end of the head into the body, said positioning and pushing means being controlled by the movement of the feeding means.

2. In a machine of the class described, in combination, means for inserting heads in tubular box bodies, comprising a support for the body, means for feeding a head to the body, means for positioning the advance end of the head in the body, means for pushing the rear end of the head into the body, the positioning means being controlled by the forward movement of the feeding means, and the pushing means being controlled by the rearward movement of the feeding means.

3. In a machine of the class described, in combination, a support for a box body, means for feeding a head to the body, means for tilting the advance end of the head into the body, and means for pushing the rear end of the head into the body.

4. In a machine of the class described, in combination, a magazine for heads, means for moving box bodies in succession past the magazine, means for feeding heads to the successive bodies, means for inserting the heads in the bodies, the inserting means

including a member for tilting the forward ends of the heads into the bodies, and means for pushing the heads into the bodies.

5. In a machine of the class described, in combination, a support for the body, a magazine for heads, a feed slide for moving the heads in succession from the magazine, means controlled by the forward movement of the slide for guiding the edge of the head remote from the slide into the body, and means controlled by the rearward movement of the slide for pushing the head in the end of the body.

6. In a machine of the class described, in combination, a support for the body, a magazine for heads, a feed slide for moving the heads in succession from the magazine, means controlled by the forward movement of the slide for guiding the edge of the head remote from the slide into the body, and means controlled by the rearward movement of the slide for pushing the head in the end of the body, said first named means comprising a tilting member engaging the forward edge of the head as the slide moves toward the body to guide the edge to place.

7. In a machine of the class described, in combination, means for inserting heads in tubular box bodies, comprising a support for the body, means for feeding a head to the body, means for positioning the advance end of the head in the body, means for pushing the rear end of the head into the body, said positioning and pushing means being controlled by the movement of the feeding means, and means for holding the head substantially horizontal until it is above the box body.

8. In a machine of the class described, in combination, means for inserting heads in tubular box bodies, comprising a support for the body, means for feeding a head to the body, means for positioning the advance end of the head in the body, means for pushing the rear end of the head into the body, the positioning means being controlled by the forward movement of the head, and the pushing means being controlled by the rearward movement of the head, and means for holding the head substantially horizontal until it is above the box body.

9. In a machine of the class described, in combination, a support for a box body, means for feeding a head to the body, means for tilting the advance end of the head into the body, means for pushing the rear end of the head into the body, said tilting and pushing means being controlled to operate in succession by the feeding means, and means for holding the head substantially horizontal until it is above the body.

10. In a machine of the class described, in combination, means for inserting heads in the ends of tubular box bodies, means for feeding the heads above the bodies and into

registry therewith in a substantially horizontal plane, means for pushing the forward edge of the head into the body, and means for afterwards pressing the rear edge into the body.

11. In a machine of the class described, in combination, means for inserting heads in the ends of tubular box bodies, means for feeding the heads above the bodies and into registry therewith in a substantially horizontal plane, means for pushing the forward edge of the head into the body, means for afterwards pressing the rear edge into the body, and controlled by the feeding of the head.

12. In a machine of the class described, in combination, a support for a box body, a head magazine, means for feeding heads from the magazine toward a box body on the support, and means adapted to insert the head in the box body by a tilting movement of the head in opposite directions, said inserting means including two means operatively timed in operation, one to tilt the head in one direction and the other to tilt the head in the opposite direction.

13. A machine of the character described including, in combination, means adapted to feed box bodies, a plurality of devices for supplying heads, and means adapted to insert into each body a head from one of said supply devices after a head from another of said supply devices, said inserting means including mechanism movable to press one side of a head into a body and thereafter press the remainder thereinto.

14. A machine of the character described including, in combination, means adapted to feed box bodies, a plurality of devices for supplying heads, and means adapted to insert into each body a head from one of said supply devices after a head from another of said supply devices, said inserting means including a reciprocal head-supporting pusher having a tooth adapted to engage the under face of the supported head to cause the head to advance with said pusher toward the body to receive the same.

15. A machine of the character described including, in combination, means adapted to feed box bodies, a plurality of devices for supplying heads, means adapted to insert into each body a head from one of said supply devices after a head from another of said supply devices, said inserting means including mechanism movable to press one side of a head, from one of said supply devices, into a body and thereafter press the remainder thereinto, and a reciprocal pusher having a tooth adapted to engage the under face of a head from another of said supply devices and deliver the same into a body having a head previously inserted therein.

16. A machine of the character described

including, in combination, means adapted to feed box bodies, a plurality of devices for supplying heads, means adapted to insert into each body a head from one of said supply devices after a head from another of said supply devices, said inserting means including mechanism movable to press one side of a head, from one of said supply devices, into a body and thereafter press the remainder thereinto, a reciprocal pusher having a tooth adapted to engage the under face of a head from another of said supply devices and deliver the same into a body having a head previously inserted therein, and means adapted to coordinate the operation of said means and devices to cause insertion of heads from each of said respective supply devices simultaneously in a plurality of bodies.

17. A machine of the character described including, in combination, means adapted to feed box bodies, a plurality of devices for supplying heads, means adapted to insert into each body a head from one of said supply devices after a head from another of said supply devices, said inserting means including a finger and a plate adapted to move into and out of the bodies and to press opposite sides of the heads from one supply device into the bodies, and means to cause the pressing operations of said finger and plate in sequence.

18. A machine of the character described including, in combination, means adapted to feed box bodies, a plurality of devices for supplying heads, means adapted to insert into each body a head from one of said supply devices after a head from another of said supply devices, said inserting means including a finger and a plate adapted to move into and out of the bodies and to press opposite sides of the heads from one supply device into the bodies, means to cause the pressing operations of said finger and plate in sequence, and means including a reciprocal presser foot adapted yieldingly to hold heads in position to be pressed by said finger into the bodies.

19. A machine of the character described including, in combination, means adapted to feed box bodies, a plurality of devices for supplying heads, means adapted to insert into each body a head from one of said supply devices after a head from another of said supply devices, said inserting means including a finger and a plate adapted to move into and out of the bodies and to press opposite sides of the heads from one supply device into the bodies, means to cause the pressing operations of said finger and plate in sequence, and means including a reciprocal presser foot adapted yieldingly to hold heads in position to be pressed by said finger into the bodies, said foot having an

extension adapted to cooperate with said plate to be lifted by the latter as the plate moves out of the body.

20. A machine of the character described including, in combination, means adapted to feed box bodies, a plurality of devices for supplying heads, means adapted to insert into each body a head from one of said supply devices after a head from another of said supply devices, said inserting means including a finger and a plate adapted to move into and out of the bodies and to press opposite sides of the heads from one supply device into the bodies, means to cause the pressing operations of said finger and plate in sequence, means including a reciprocal presser foot adapted yieldingly to hold heads in position to be pressed by said finger into the bodies, said foot having an extension adapted to cooperate with said plate to be lifted by the latter as the plate moves out of the body, said extension having a notch for reception of said plate.

21. A machine of the character described including, in combination, means adapted to feed box bodies, a plurality of devices for supplying heads, means adapted to insert into each body a head from one of said supply devices after a head from another of said supply devices, said inserting means including a finger and a plate adapted to move into and out of the bodies and to press opposite sides of the heads from one supply device into the bodies, means to cause the pressing operations of said finger and plate in sequence, and a reciprocal pusher having a tooth adapted to engage the under faces of heads from another of said supply devices and deliver the heads into bodies previously supplied with heads from the other supply device.

22. A machine of the character described including, in combination, a reciprocal head feeding slide, a head pressing finger mounted to rock into and out of the end of a box body at one side of said body, a plate movable into and out of a different portion of the same end of the box body, and means adapted to move said finger and plate to press first one side and then the opposite side of said head into the box body and thereafter move said finger and plate out of the box body, said means including an oscillatable arm operatively connected to said plate, a spring operatively connected to move said arm in one direction and a power actuated, reciprocal, operating bar having a spring pressed catch for moving said arm in opposition to said spring.

23. A machine of the character described including, in combination, a reciprocal head feeding slide, a head pressing finger mounted to rock into and out of the end of a box body at one side of said body, a plate

movable into and out of a different portion of the same end of the box body, and means adapted to move said finger and plate to press first one side and then the opposite side of said head into the box body and thereafter move said finger and plate out of the box body, said means including an oscillatable arm operatively connected to said plate, a spring operatively connected to move said arm in one direction and a power actuated, reciprocal, operating bar having a spring pressed catch for moving said arm in opposition to said spring, a presser foot, a spring for pressing said foot against a head adjacent the body to receive such head, said first mentioned spring being stronger than the latter, said foot having an extension adapted to be actuated by said plate to lift said foot against opposition of the latter's spring.

24. A machine of the character described including, in combination, a reciprocal head feeding slide, a head pressing finger mounted to rock into and out of the end of a box body at one side of said body, a plate movable into and out of a different portion of the same end of the box body, means adapted to move said finger and plate to press first one side and then the opposite side of said head into the box body and thereafter move said finger and plate out of the box body, said means including an oscillatable arm operatively connected to said plate, a spring operatively connected to move said arm in one direction and a power actuated, reciprocal, operating bar having a spring pressed catch for moving said arm in opposition to said spring, a presser foot, a spring for pressing said foot against a head adjacent the body to receive such head, said first mentioned spring being stronger than the latter, said foot having an extension adapted to be actuated by said plate to lift said foot against opposition of the latter's spring, and means to guide said plate into the box body including a guide bar upstanding from said plate between the shaft of said oscillatable arm and the front end of said foot.

25. A machine of the character described including, in combination, a reciprocal head feeding slide, a head pressing finger mounted to rock into and out of the end of a box body at one side of said body, a plate movable into and out of a different portion of the same end of the box body, means adapted to move said finger and plate to press first one side and then the opposite side of said head into the box body and thereafter move said finger and plate out of the box body, said means including a rock shaft to which said finger is operatively connected having an arm, a power actuated reciprocal, operating bar adapted to actuate said arm to rock said shaft in one direction, and a spring

operatively connected to rock said shaft in the opposite direction.

26. A machine of the character described including, in combination, a reciprocal head feeding slide, a head pressing finger mounted to rock into and out of the end of a box body at one side of said body, a plate movable into and out of a different portion of the same end of the box body, means adapted to move said finger and plate to press first one side and then the opposite side of said head into the box body and thereafter move said finger and plate out of the box body, said means including rock shafts to which said finger and plate are operatively connected, respectively, a power actuated, reciprocal, operating bar adapted to rock each of said shafts in one direction, springs for rocking said shafts in the opposite direction.

27. A machine of the character described including, in combination, a reciprocal head feeding slide, a head pressing finger mounted to rock into and out of the end of a box body at one side of said body, a plate movable into and out of a different portion of the same end of the box body, means adapted to move said finger and plate to press first one side and then the opposite side of said head into the box body and thereafter move said finger and plate out of the box body, said means including rock shafts to which said finger and plate are operatively connected, respectively, a power actuated, reciprocal, operating bar adapted to rock each of said shafts in one direction, and springs for rocking said shafts in the opposite direction.

28. A machine of the character described including, in combination, a reciprocal head feeding slide, a head pressing finger mounted to rock into and out of the end of a box body at one side of said body, a plate movable into and out of a different portion of the same end of the box body, means adapted to move said finger and plate to press first one side and then the opposite side of said head into the box body and thereafter move said finger and plate out of the box body, said means including rock shafts to which said finger and plate are operatively connected, respectively, a power actuated, reciprocal, operating bar adapted to rock each of said shafts in one direction, and springs for rocking said shafts in the opposite direction, said operating bar having a spring pressed catch and the rock shaft connected to said plate having an arm adapted to be engaged by said catch to rock said arm in opposition to its spring, a presser foot having an extension overlying said plate, and a spring for pressing said foot into engagement with a head adjacent a box body, said plate having a guide bar extending between and adapted to contact one of said rock shafts and the extension of said foot.

29. A machine of the character described including, a support for a box body, and head inserting mechanism comprising two fingers each adapted to press on a head to insert same in a box body, and means adapted to impart inserting movement to each of said fingers and cause the part of the head engaged by one finger to be inserted before insertion of the complete head.

30. A machine of the character described including, a support for a box body, a presser foot adjacent the box body for yieldingly holding a head, a plurality of fingers adapted to move into and out of the box body and press a head into the box body, and means adapted to cause said fingers and foot to cooperate to insert a head in said body, one side of said head before the other.

In testimony whereof I affix my signature.

CHRIST L. NUERMBERGER.
